SHELF ARRANGEMENT

Lyman F. Whitney, Cambridge, Mass., assignor,
by mesne assignments, to Stator Corporation,
a corporation of Rhode Island

Application March 29, 1938, Serial No. 198,637

3 Claims. (Cl. 211—143)

This invention relates to an improved sliding shelf arrangement, and more particularly to such an arrangement for a refrigerator cabinet.

In accordance with this invention, a shelf may be supported in a cabinet or the like so that the shelf may be slid part way out of the cabinet in order to afford more convenient access to articles on the shelf, but so that movement of the shelf out of the cabinet is normally prevented. Thus, accidental separation of the shelf from the cabinet is avoided. On the other hand, the present invention affords simple means including a retainer which may be manipulated to permit the shelf to be tipped slightly and then removed entirely from the cabinet; for example, for cleaning or the like.

To permit these desirable results, a plurality of supports are preferably provided upon which the shelf may slide. At one side of the cabinet there may be two supports, which may conveniently be in the form of metal knobs, over which the side bar of the shelf slide. At the same side of the cabinet there may be an additional protuberant member or knob disposed above the members which slidably support the shelf, and a retainer may be disposed beneath this upper knob in such a manner that the end of the shelf is constrained to follow a substantially straight-line path and to engage the upper protuberant member or knob as an abutment which limits the outward movement of the shelf. The retainer may conveniently be in the form of a simple hasp-like wire member. This member may be readily detached from one of the supporting knobs so that thereupon the shelf may be tipped slightly to permit its rear portion to clear the upper knob so that the shelf is no longer constrained to follow a straight-line path, but can be removed from the cabinet.

In the accompanying drawing:

Fig. 1 is a horizontal sectional view of the cabinet provided with a shelf arrangement constructed in accordance with this invention, the partially projected position of the shelf being indicated in dash lines;

Fig. 2 is a broken horizontal sectional detail of a portion of the shelf-supporting means and of the side of the shelf;

Fig. 3 is a broken elevational view of the assembly shown in Fig. 2, certain parts being shown in dot and dash lines; and

Fig. 4 is a section on line 4—4 of Fig. 3.

The accompanying drawing shows a typical refrigerator cabinet with which the present invention may be employed. Such a cabinet is

provided with a rear wall 1 with opposite side walls 2 and with a swinging front door (not shown). In accordance with this invention, a shelf 4 may be slidably mounted in the cabinet. This shelf may comprise a perimetric wire frame 7, preferably formed of round wire stock, and may be provided with a plurality of flat wire slats 8 extending between the front and rear rails of the frame. As viewed in Fig. 1, the right-hand side of the shelf may be supported in any suitable manner, as upon three knobs 10^a, 11^a and 12^a. These knobs are provided with round shanks on which the corresponding side bar of the shelf may slide.

At the opposite side of the cabinet there may be a knob 10 opposite and similar to the knob 10^a. Behind the knob 10 I also provide knobs 11 and 12 which are mutually spaced. The knobs 11 and 12 may be similar and may provide round portions over which the corresponding side rail 20 of the shelf may slide. These knobs, however, are provided with extensions 14, as shown in Fig. 2.

Disposed slightly above the knobs 11 and 12 is an upper protuberant member or knob 16. This knob may be provided with a head 16^a which has a somewhat greater diameter than its shank portion. This shank portion of the knob 16 is so disposed that the upper portion of the corresponding side rail of the shelf may be spaced 30 only slightly below the shank when the shelf slides forwardly in its own plane. The perimetric frame 7 of the shelf 4 may be provided with curved corners such as shown, for example, in dotted lines in Fig. 2, it being evident that a 35 rear corner of the forwardly moving shelf engages the head 16^a of the knob 16, which acts as a stop, when the shelf follows a straight-line sliding path.

In order to constrain the shelf so that it normally follows such a path, a retainer 20 is provided. This retainer, as shown in Fig. 2, may be in the form of a hasp-like wire member providing a wire loop pivotally mounted on a shallow peripheral groove of the shank 14 of the knob 45 12. The opposite end of the retainer 20 is provided with a downturned end portion 21 which hooks over a correspondingly grooved portion of the knob 11.

When the retainer 20 is in normal position it 50 prevents the rear of the shelf from being tipped downwardly. Accordingly, the shelf under these conditions must follow a substantially straight-line path in its own plane as it is being slid forwardly. As this movement of the shelf is 55

continued, the curved corner portion of the perimeter frame engages the head 16^a of the knob 16, which acts as an abutment or stop to limit the forward movement of the shelf. This position of the shelf is shown in dotted lines in Fig. 1.

It is of course obvious that if preferred a knob corresponding to the knob 16 may be similarly disposed at the opposite side of the cabinet, and furthermore that if preferred the knobs 11^a and 12^a could be made similar to the knobs 11 and 12 and also provided with a hasp-like retainer 20.

It is evident that the retainer 20 is readily accessible between the side rail of the frame 7 and the adjoining flat wire 8, as shown in Figs. 1 and 4. When, for example, it is desired to remove the shelf for cleaning, the retainer 20 is unhooked from the knob 11 and may swing downwardly to the depending position indicated in dot and dash lines in Fig. 3. Thereupon, the rear end of the shelf may be swung downwardly, while the front of the shelf is being tipped upwardly, to permit the shelf to be removed from the cabinet. The position of the rear portion of the shelf as it is being moved away from the knob 16 in this manner is shown in dash lines in Fig. 3.

It is evident that the present invention affords a simple and inexpensive arrangement for slidably supporting a shelf in a refrigerator cabinet. This arrangement permits the shelf readily to be slid to a partially projected position, wherein the articles supported on the shelf are more readily accessible, but the movement of the shelf entirely out of the cabinet is positively prevented under normal conditions by the knob 16 and the retainer 20. However, when the retainer is swung into its inoperative position, the shelf may be readily removed for cleaning or the like.

I claim:

1. In a housing having opposite side walls, a shelf mounted for slidable movement between said walls, supporting means upon one of said walls slidably supporting the corresponding side of the shelf, two spaced supports projecting inwardly from the opposite wall and slidably supporting the corresponding side of the shelf, an upper protuberant element projecting inwardly from the last-named side wall over the space between the said supports, said element being adapted to engage the rear portion of the shelf to act as a stop and limit the outward movement of the shelf when the latter is slid outwardly substantially within its own plane, and a retainer normally positioned below said element and constraining the shelf to follow a path within its own plane, said retainer being removable from its normal position to permit the shelf to be tipped

relative to its normal plane so that its rear portion may clear the protuberant element and the shelf may then be removed from the housing.

2. In a housing having opposite side walls, a shelf mounted for slidable movement between said walls, supporting means upon one of said walls slidably supporting the corresponding side of the shelf, two spaced supports projecting inwardly from the opposite wall and slidably supporting the corresponding side of the shelf, an upper protuberant element projecting inwardly from the last-named side wall over the space between the said supports, said element being adapted to engage the rear portion of the shelf to act as a stop and limit the outward movement of the shelf when the latter is slid outwardly substantially within its own plane, and a retainer normally extending between the supports and below the corresponding side of the shelf, said retainer having an end pivotally mounted on one of said supports and an opposite end normally engaging the other support, said retainer then being positioned to cooperate with the protuberant element in constraining the shelf to follow a path substantially in its own plane, said retainer being swingable from its normal position to permit the shelf to be tipped out of said path so that the rear portion thereof may clear the protuberant element and the shelf may be removed from the housing.

3. In a housing having opposite side walls, a shelf mounted for slidable movement between said walls, supporting means upon one of said walls slidably supporting the corresponding side of the shelf, two spaced supports projecting inwardly from the opposite wall and slidably supporting the corresponding side of the shelf, an upper protuberant element projecting inwardly from the last-named side wall over the space between the said supports, said element being adapted to engage the rear portion of the shelf to act as a stop and limit the outward movement of the shelf when the latter is slid outwardly substantially within its own plane, and a hasp-like wire retainer pivotally mounted on one of said supports and normally having a hook-like engagement with the other support, said retainer normally cooperating with the protuberant element in constraining the shelf to follow a path substantially in its own plane, the hook-like end of the retainer being detachable from the corresponding support so that the shelf may then be tipped so that its rear portion may clear the protuberant element and the shelf may be removed from the housing.

LYMAN F. WHITNEY.
